FUSED CUTOUT

Edward H. Yonkers, Chicago, Ill., assignor to
Joslyn Manufacturing and Supply Company,
Chicago, Ill., a corporation of Illinois

Application October 1, 1945, Serial No. 619,657

25 Claims. (Cl. 200—114)

1

The present invention relates to fused cutouts, and has for one of its objects the provision of an improved cutout of the dropout type which is of simple and rugged construction, is thoroughly reliable in operation, and in which the fuse tube assembly may be easily and quickly mounted upon or detached from the spaced terminals of the insulator assembly. This application is a continuation in part of copending application Serial No. 567,021, filed December 7, 1944.

It is another object of the present invention to provide an improved and simple mechanism for quickly withdrawing the fuse link conductor from the fuse tube of the cutout when the fuse link is ruptured and for normally restraining the fuse tube assembly against dropout movement.

According to another object of the invention, the biasing means for the fuse extracting mechanism is arranged to perform the additional function of guiding both ends of the fuse tube assembly into engagement with the terminals of the insulating support as the fuse tube assembly is mounted upon the insulating support.

In accordance with still another object of the invention, the means for biasing the fuse extracting mechanism is detached from the fuse tube assembly and serves normally to restrain the fuse tube assembly against dropout movement and also to produce pressure engagement between the current conducting and engaged hinge parts of the two assemblies so long as the fuse extracting mechanism is not operated.

It is a further object of the invention to provide a cutout of the character described wherein the fuse tube assembly is comprised of rigidly related parts and dropout movement of the assembly is effected by lateral movement of the pivoted end of the assembly incident to fuse rupture.

It is still another object of the invention to provide for use in a fused cutout, an improved fuse pigtail extracting arm which embodies exceedingly simple facilities for securely connecting a fuse pigtail conductor thereto.

The invention, both as to its organization and method of operation, together with further objects and advantages thereof, will best be understood by reference to the following specification taken in connection with the accompanying drawings, in which:

Fig. 1 is a side view, partially in section, illustrating an improved cutout characterized by the features of the present invention;

Fig. 2 is a sectional view taken along the lines 2—2 of Fig. 1;

Fig. 3 is a fragmentary front view further illus-

trating the lower terminal assembly of the insulating support embodied in the device;

Fig. 4 is a fragmentary bottom view of the fuse tube assembly illustrating the construction of the fuse extracting arm embodied therein;

Fig. 5 is a side view of the supporting and extracting arms forming a part of the fuse tube assembly;

Fig. 6 is a curve illustrating one of the operating characteristics of the device;

Fig. 7 is a fragmentary side view illustrating a modified form of the invention;

Fig. 8 is a sectional view taken along the lines 8—8 of Fig. 1; and

Fig. 9 is a sectional view taken along the lines 9—9 of Fig. 7.

Referring now to the drawings, and more particularly to Figs. 1 through 5 thereof, the present improved fused cutout is there illustrated as comprising the usual insulating support in the form of a petticoat insulator 10 having a center zone longitudinally thereof clampingly embraced by a bracket 11 which may be utilized in supporting the cutout upon a pole or another suitable supporting structure. At its respective upper and lower ends the insulating support 10 is provided with spaced apart upper and lower terminals indicated generally at 12 and 18, respectively, and between which a fuse tube assembly 24 of the expulsion type is adapted to be supported.

Specifically, the upper terminal 12 comprises a conductive channel member of U-shaped cross section throughout its length having an integrally formed half collar 12a at one end thereof for embracing the collar seat provided at the upper end of the insulating support 10. This portion of the terminal 12 is clamped against the seating surface of the support 10 by means of a half collar clamping member 13 and clamping screws 13a disposed upon opposite sides of the support 10. At the laterally extended end thereof, the upper terminal member is provided with downwardly extending hood skirts 12c and 12d, the upper portions of which are arranged in meeting engagement with an overhanging lip 12e extending downwardly from the top member 12. Thus, the parts 12c, 12d and 12e define a hooded or partially enclosed space at the extended end of the terminal member 12 for receiving therewithin the upper end of the fuse tube assembly 24. To prevent this end of the fuse tube assembly from being moved beyond a predetermined point longitudinally of the skirts 12c and 12d as the assembly is swung into its closed circuit position, a stop pin 12b is provided which extends transversely

between the two identified skirts. This pin is arranged to coact with a retaining element in the form of a double leaf spring catch member 14 to restrain the fuse tube assembly 24 against pivotal dropout movement to the open circuit position thereof. At one end, the two leaves of the spring 14 are anchored to the under side of the upper terminal member by means of a terminal screw 15 which is threaded through a reinforced top side portion of the terminal member. Upward travel of the retaining element 14 during dropout movement of the assembly 24 is limited by an adjustable stop screw 14b threaded through the top wall of the member 12 to engage the element 14 intermediate its ends. A clamping washer 17 and nut 16 threaded onto the screw 15, may be utilized to establish line wire connections with the upper terminal member.

The detachable fuse tube assembly 24 comprises the usual expulsion fuse tube 25 formed of an inner layer of pressed fibre or the like, having good arc extinguishing gas evolving properties, and an outer layer of Bakelite impregnated paper having excellent insulating properties. At its upper end, this fuse tube is provided with a terminal ferrule 28 having a threaded end portion for receiving the internally threaded terminal cap 29. This cap acts as a tube end part engageable with the retaining element 14 to restrain the fuse tube assembly against dropout movement. To insure seating of the cap in a fixed position and thus prevent variations in the distance between the upper end of the cap and the point of pivotal support of the fuse tube assembly, the ferrule 28 is provided with an inwardly directed shoulder 28a against which the lower rim 29a of the cap may be tightly screwed. The two terminal parts 28 and 29 are arranged to have the head 30a of a fuse link 30 clampingly held therebetween internally of the fuse tube 25. Specifically, the head 30a of the link is clamped against the upper end of the ferrule by means of coil spring 29b which extends downwardly from and is permanently attached to the top wall of the cap 29 internally of the cap. This fuse link, which preferably is of the improved form disclosed and claimed in applicant's copending application, Serial No. 533,824, filed May 3, 1944, now Patent No. 2,453,688 granted Nov. 9, 1948, is provided with a pigtail conductor 31 extending longitudinally of the tube 25 and out of the open lower end of this tube.

The tube 25 is arranged to be supported by a laterally extending and conductive supporting arm 26 which is of inverted T-shaped cross section throughout the major portion of its length. This supporting arm is provided with a ferrule 26e through which the lower open end 25a of the fuse tube 25 is driven to provide a pressed fit connection therebetween. Interengageable hinge parts respectively mounted upon the lower terminal 18 of the insulating support 10 and the extended end of the supporting arm 26 are provided for pivotally supporting the fuse tube assembly 24 upon the insulating support 10. Specifically, the lower insulator terminal 18 is comprised of two half-cup parts 18a and 18b which are screw clamped to embrace the lowermost petticoat of the insulator 10. The terminal part 18b is provided with hinge means in the form of two transversely spaced apart, hook shaped brackets 19 and 21 having elongated and aligned trunnion receiving seats 19a and 21a formed therein which extend substantially normal to the longitudinal axis of the fuse tube 25. These

brackets also respectively include guide noses 19b and 21b which are utilized in the manner explained below to guide the hinge trunnions of the fuse tube assembly 24 into engagement with the seats 19a and 21a. The other part 18a of the lower terminal 18 is provided with a downwardly extending portion having spaced apart parallel sides 18c within which is supported the curved portion 20c of a U-shaped and twin leaf tensioning spring 20. This portion of the terminal part 18a is also used to mount the clamping parts of a line terminal assembly 22 in an obvious manner. The U-shaped tensioning spring 20 is held assembled with the terminal part 18a by means of an assembly pin 18d fixedly anchored to the bottom wall of the terminal part 18b.

As indicated above, the hinge parts of the fuse tube assembly 24 comprise a pair of trunnions 26c and 26d located at the extended end of the supporting arm 26 and extending transversely outward therefrom. More specifically, the supporting arm 26 is provided at its extended end with a forked portion comprising transversely spaced end parts 26a and 26b having the trunnions 26c and 26d formed integral therewith at their respective ends. The two identified trunnions are adapted for pivotal and sliding engagement with the elongated trunnion seats 19a and 21a, respectively, of the two brackets 19 and 21. They are flattened along the upper sides thereof, as indicated at 28e for the trunnion 26c, in order to prevent removal from the trunnion seats or placement thereon except when the fuse tube assembly occupies its lowered or released position.

For the purpose of rapidly withdrawing the fuse link conductor or pigtail 31 from the fuse tube 25 upon rupture of the fusible element of the link, there is provided a one-piece fuse extracting arm 33 which is die formed from flat resilient strip metal stock, such for example, as Phosphor bronze, is pivotally supported upon the arm 26 and is substantially coextensive in length therewith. The main part of this arm is bent into the configuration shown in Figs. 4 and 5 of the drawings to have parallel extending intermediate and return bent portions 33a and 36, a loop-shaped end bridge 35, and an end pivot piece 33c which is bent around a pivot pin 33d seated within aligned bearing openings bored centrally of the trunnions 26c and 26d. Thus the extracting arm 33 has the same axis of rotation as the fuse tube assembly 24. Intermediate the ends of the arm 33, means comprising a headed tie post 32 are provided for securely connecting a fuse link pigtail conductor 31 to the arm. Specifically, the post 32 is fixedly mounted upon the intermediate portion 33a of the arm and extends downwardly through a slot opening 38a in the return bent portion 36 of the arm. The dimensions of this slot opening are slightly greater than the cross sectional dimensions of the post 32, thus permitting unrestricted movement of the arm portion 36 toward and away from the arm portion 33a. At its extended end, the post 32 fixedly supports a flat pigtail retaining head 32a having its ends 32b bent slightly over the side edges of the arm portion 36. The tie post 32 and head 32a serve normally to stress the arm portion 36 toward the arm portion 33a, so that when a fuse pigtail conductor 31 is wrapped around the post 32 it is clamped against the underside of the head 32a by the arm portion 36.

In order to tension the fuse link conductor 31 through the arm 33, camming means are formed integral with this arm to coact with the spring

20 in producing a downwardly directed pull upon the conductor 31 as the fuse tube assembly is rotated into its closed circuit position. Specifically, this camming means comprises a substantially flat segment 33b and a curved segment 33e interposed between the pivot pin 33d and the straight intermediate portion 33a of the arm 33. These camming segments are normally disposed between the spaced apart end parts 25a and 26b of the supporting arm 26 to be engaged by the lip end 20b of the spring leg 20d which extends between the two hinge brackets 19 and 21. As explained more fully below, the shape of the camming segments 33b and 33e of the arm 33 is of considerable importance in obtaining the desired pull upon the fuse link conductor 31, preventing this conductor from being tensioned in excess of a predetermined pull, and insuring pigtail conductor extraction in the event the extracting arm 33 is partially pivoted away from the supporting arm 26 as a result of stretching of the pigtail conductor and fuse link during prolonged service of the cutout without refusing.

In order to provide for switch stick manipulation of the hinge trunnions 26c and 26d into engagement with the trunnion seats of the brackets 19 and 21, respectively, the upstanding center part of the T-shaped supporting arm 26 is enlarged at a point adjacent the forked end of the arm to provide for the formation of an opening therein into which the hook of a switch stick may be inserted. This opening is comprised of a first part 27a of enlarged diameter through which the switch stick hook may be inserted, and an offset part 27b of smaller diameter into which the shank portion of the hook may be projected to prevent disengagement of the hook and the fuse tube assembly. To facilitate swinging of the fuse tube assembly into and out of its closed circuit position, the upper terminal member or ferrule 28 of this assembly is similarly provided with an enlarged and integrally formed loop 28b into which the hook of a switch stick may be readily inserted.

From the above explanation it will be apparent that when the fuse tube assembly 24 is detached from the terminals of the insulating support 10, the supporting arm 26 and the extracting arm 33 are freely rotatable relative to each other. When it is desired to fuse the assembly 24, the terminal cap 29 is unscrewed from the ferrule 28 and a fuse link 30 inserted within the chamber of the tube 25 so that the pigtail conductor 31 thereof projects out of the open lower end 25a of the tube. Following this operation, and with the extracting arm 33 firmly engaged against the supporting arm 26, the projecting end of the conductor 31 is carried over the bridge portion 35 of this arm, tensioned and wrapped around the tie post 32 between the arm portion 36 and the head 32a. One or more turns may be taken around the post 32 as desired. As the turns are taken around the post 32 the arm part 36 is moved toward the arm part 33a, thus deforming the connected parts 33a, 35 and 36 so that the turns are tightly squeezed between the arm part 36 and the head 32a, thereby frictionally to hold the conductor turns against slippage. Thus, the pigtail conductor serves tightly to hold the arm 33 in engagement with the underside of the supporting arm 26. After the described operations are completed, the terminal cap 29 may be threaded onto the ferrule 28 until the cap rim 29a abuts the shoulder 28a, thereby to establish the exact desired distance between the top of the cap and the axis of the trunnions 26c and 26d. As the cap 29 is screwed onto

the ferrule 28, the spring 29b is compressed to clamp the head 30a of the fuse link tightly against the upper end of the ferrule.

In order to mount the fuse tube assembly 24 upon the terminals of the insulating support 10, the hook of a switch stick is first inserted through the opening 27a to bring the shank portion of the hook into registry with the opening part 27b of reduced diameter. Interlocking of the hook shank 10 with the sides of the small diameter opening 27b serves to prevent inadvertent removal of the assembly 24 from the end of the switch stick. In this regard it is noted that the switch hook opening is positioned along the supporting arm 26 adjacent the extended end thereof so that as the switch hook is elevated to raise the assembly 24, the center of gravity of the assembly is well below the hook, thus providing for maintenance of the interlocked connection between the hook and the small diameter opening 27b, and for easy manipulation of the trunnions 26c and 26d into engagement with the brackets 19 and 21 of the lower terminal 18. As these trunnions are manipulated to bring the same into engagement with the identified brackets, they are first engaged with the guide noses 19b and 21b of the brackets. Concurrently with such engagement, the upturned lip 20b of the biasing spring 20 engages the camming surface 33b of the extracting arm 33. Thus, as the assembly 24 is manipulated to push the extended end of the arm 26 toward the brackets 19 and 21, the spring 20, through its engagement with the extracting arm 33, functions to guide the trunnions 26c and 26d into seating engagement with the seats 19a and 21a.

After the assembly 24 is thus pivotally mounted upon the lower terminal 18 of the insulating support 10, the hook of the switch stick may be withdrawn from the openings 27a and 27b and 25 inserted into the opening of the loop 28b for the purpose of rotating the assembly 24 about the trunnions 26c and 26d into its closed circuit position. As the fuse tube assembly 24 is rotated in a counter clockwise direction to its closed circuit position, the arm 20d of the biasing spring 20 rides up the camming surfaces 33b and 33e of the extracting arm 33. Thus, the spring 20 is caused to react between the support 10 and the extracting arm 33 to perform three additional functions. First, it forces the trunnions 26c and 26d forward along the seats 19a and 21a toward the noses 19b and 21b of the brackets 19 and 21, thereby to position the fuse tube end part 29 for interlocking engagement with the retaining element 14. Secondly, it biases the bridge end 35 of the extracting arm 33 away from the supporting arm 26 to tension the pigtail conductor 31 and hence the fusible element within the fuse link 30. Thirdly, it functions to force the trunnions 26c and 26d into pressure engagement with the forward ends of the bracket seats 19a and 21a. Such pressure engagement between the two identified trunnions and their engaging brackets serves accurately to center the upper end of the fuse tube assembly 24 relative to the front or entrance opening between the skirts 12c and 12d of the upper terminal 12. Thus, the upper end of the assembly 24 is, through the action of the spring 20, forced into a setting such that regardless of the direction from which the upward pivoting force is imposed upon the assembly, it will move between the skirts 12c and 12d during the final pivotal movement of the assembly into its closed cir-

cuit position. As the tube end part 29 moves between the skirts 12c and 12d, it engages the catch portion 14a of the retaining element 14 and rides beneath this portion of the element until it is brought to bear against the stop part 12b. During final movement of the tube end part 29 toward the stop part 12b, the tube end part 29 rides beneath the lip 14a and seats against the under side of the element 14 to deform this element upward about the end of the stop screw 14b. With the spring element thus deformed, it exerts a thrust longitudinally of the tube 25 having a component which tends to move the trunnions 26c and 26d to the left. Such movement is prevented by engagement of the arm camming portion 33e with the spring part 20b. The upper end of the fuse tube assembly is prevented from rotating away from the closed circuit position thereof through its engagement with the lip 14a of the element 14.

Thus, the fuse tube assembly 24 is fixedly mounted upon the insulating support 10 to provide a fused current path between the two terminals 12 and 18. Specifically, this path extends from the terminal screw 15 through the conductive arm 12 and the spring 14 to the terminal cap 29. From this point, the conductive path extends through the fusible element of the link 30 by way of the flexible pigtail conductor 31, the extracting arm 33, the spring 20 and brackets 19 and 21, and the conductive terminal parts 18a and 18b to the line terminal assembly 22. It will be noted that the spring 14 thrusting down on the fuse tube and the spring 20 thrusting against the camming portion of the arm 33 serve to hold all contacting parts of the fuse tube assembly and insulator terminals in pressure engagement, thereby to minimize contact resistance therebetween.

So long as current flow over the described conductive path between the terminals 12 and 18 does not exceed the current-time fusing characteristic of the link 30, the fusible element within the link 30 serves mechanically to hold the extracting arm 33 in its set position against the underside of the supporting arm 26. When, however, this fusible element is required to carry current in excess of a predetermined magnitude for more than a predetermined interval, it is ruptured to relieve the holding force imposed upon the extracting arm 33 through the pigtail 31. The spring 20, in reacting between the support 10 and the camming surfaces of the arm 33 is thus rendered operative rapidly to rotate the arm 33 downwardly about the pivot pin 33d, thereby to withdraw the pigtail conductor 31 from the lower end of the fuse tube 25. In this regard it is noted that the arm 33 is of substantial length, such that rotation thereof through a relatively small angle produces a relatively large displacement between the bridge end 35 thereof and the lower end of the tube 25. Further, this arm is of small mass and hence has little inertia, thus insuring rapid acceleration of the bridge end 35 thereof away from the lower end of the fuse tube 25. In fact, the arm 33 and the spring 20 are preferably so designed that the arc is sufficiently elongated during the first voltage half cycle following fuse rupture to prevent breakdown of the gap during the next succeeding voltage half cycle. Further, the length of the extracting arm 33 and the angle of movement of the bridge end 35 thereof is such that, under any and all conditions of fuse rupture, all

of the pigtail conductor 31 and the lower unfused segment of the fuse link are completely removed at high speed from the bore of the fuse tube 25 to hang downwardly in alignment with the long axis of the insulating support 10. This arrangement is to be distinguished from conventional dropout cutouts wherein only partial pigtail conductor extraction is produced incident to fuse rupture.

As the arm 33 is rotated to a position approximately normal to the supporting arm 26, the camming surface 33b thereof tends to move away from the spring part 20b, thus relieving the force holding the trunnions 26c and 26d at the forward ends of the horizontal trunnion seats 19a and 21a. As this force is relieved, the spring retaining element 14 in thrusting downward upon the tube end part 29, slides the trunnions away from the bracket noses 19b and 21b, i. e. to the left along the trunnion seats 19a and 21a. After the static friction between the trunnions and trunnion seats is broken and with the extracting arm camming portion disengaged from the spring part 20b, gravity forces acting upon the fuse tube assembly are sufficient to continue the movement of the trunnions until they reach the rear ends of the trunnion seats. As such movement of the trunnions occurs, the distance between the trunnions and the retaining element 14 catch portion 14a is obviously increased and the lower end of the fuse tube is moved toward the support 10 in a direction substantially transverse to the long axis of the fuse tube. Such movement of the fuse tube assembly as accompanied by angular movement of the tube end part 29 to tilt its right upper edge downward and by movement of this part away from the retaining element 14, until a point is reached where the catch 14a no longer engages the side of the tube end part 29. Thus the fuse tube assembly 24 is released for downward pivotal dropout motion about the axis of the trunnions 26c and 26d under the influence of gravity forces acting thereon.

From the above explanation it will be apparent that dropout movement of the fuse tube assembly 24 is effected, without collapsing the assembly, primarily by moving the lower pivot support transversely of the longitudinal axis of the fuse tubes to increase the distance between the point of pivotal support and the upper end retaining element 14. The importance of exactly positioning the cap 29 relative to the other parts of the assembly, i. e. in a position such that its rim 29a tightly seats against the shoulder 28a, thus becomes apparent. In this regard it is noted that the length of the trunnion seats 19a and 21a is so related to the permissible downward travel of the retaining element 14 that release of the tube end part 29 from the retaining element is assured during the described transverse sliding movement of the trunnions along the trunnion seats. Specifically, the trunnion seats 19a and 21a are of fixed uniform length. The downward travel of the retaining element 14 may, by suitable adjustment of the screw 14b through the terminal part 12, be limited as required to insure full release of the tube end part 29 from the element 14 as the trunnions move toward the rear ends of the trunnion seats.

From the above explanation it will be understood that release of the fuse tube assembly for dropout movement is accomplished upon fuse rupture by sliding the lower end of the assembly 75 to the left in a horizontal plane in order to effect

downward movement accompanied by angular tilting movement of the cap 29. The same result may be accomplished, if desired, by increasing the lengths of the trunnion seats and tilting the seats upward at the rear ends thereof so that the cap 29 is not lowered but is only tilted to move its upper right edge downward as the trunnions are slid upward along the trunnion seats under the influence of the element 14 in response to rupture of the fuse link.

Two of the problems involved in the construction of any cutout embodying a fuse extracting mechanism are those of preventing the fusible element of the link from being overstressed to change the operating characteristics of the link, and of obtaining fuse remnant extraction upon fuse rupture even though the extracting arm has moved partially away from its fuse tensioning position as a result of stretching of the fusible element and pigtail conductor of the link. The critical tension beyond which the fusible element of the link should not be tensioned varies for links of different sizes or current ratings. In general, however, it is safe to employ a pull not exceeding 12 pounds upon the pigtail conductor of a link of the smallest rating. In the illustrated embodiment of the invention, the camming parts 33b and 33e are so shaped that the pull exerted upon the pigtail conductor 31 is limited not to exceed a predetermined value. Thus it will be noted that the camming part 33b is of sharply increasing radius away from the axis of rotation of the assembly 24 and hence is effective rapidly to deform the leg 20d of the spring 20 during initial movement of the fuse tube assembly 24 toward its closed circuit position. During movement of the camming lip 20b over these camming parts of the arm 32, the tension imposed upon the fusible element of the link 30 through the conductor 31 is increased in accordance with the characteristic curve A illustrated in Fig. 6 of the drawings. Specifically, as the spring arm 20d is moved from a position in engagement with the point a along the camming part 33b to a position in engagement with the point b therealong, the tension imposed upon the fusible element of the link is rapidly increased from a zero value to a value d which may be approximately 3 or 4 pounds. During continued rotation of the assembly 24 toward its closed circuit position, the spring arm 20d rides upon the part 33e of the arm 32. This camming part is of only slightly increasing radius relative to the axis of pivotal rotation of the assembly. Accordingly, for a large angle of movement of the assembly 24, there occurs only a small increase in the deformation of the spring 20. As a result, and again referring to Fig. 6 of the drawings, the tension imposed upon the fusible element of the link is only increased the small increment d-e during movement of the arm 20d from the point b to the point c in engagement with the arm part 33e. Thus, it will be noted that after the fuse tube assembly is rotated through a predetermined angle, further rotation of the assembly towards its closed circuit position produces only a small increase in the tension imposed upon the fusible element of the link.

In accordance with a further feature of the invention, the fuse link tensioning facilities are so arranged that force is imposed upon the extracting arm 33 throughout the major portion but not the entire range of angular movement thereof. Thus the configuration of the camming parts 33b and 33e is such that during rotation of

the arm 33 to extract the conductor 31 from the fuse tube, the lip 20b of the spring 20 is biased against these parts until the arm 33 is rotated through an angle of approximately 90 degrees or to a position substantially normal to the supporting arm 26. Further, and again due to the small change in radius of the part 33e between the points b and c therealong, the biasing force acting upon the arm 32 remains substantially constant and at a high value during movement of the arm 32 through the major portion of the angle through which it may be rotated when the fusible element of the link 30 ruptures. This being true, it follows that even though the arm 33 is permitted to rotate partially away from the supporting arm 26 due to stretch of the pigtail conductor 31 and the fusible element of the link, the arm 33 will nevertheless be rapidly rotated to effect arc elongation and fuse remnant extraction when the fusible element of the link ruptures. Thus the described features all contribute to fast and positive removal of the pigtail conductor 31 from the fuse tube 25 when the fusible element of the link 30 is ruptured.

25 In the second embodiment of the invention illustrated in Fig. 7 of the drawings, substantially all of the above-described operating features are provided, together with modified facilities for effecting fuse tube dropout movement incident to fuse rupture. Aside from the structural differences pointed out immediately below, this embodiment of the invention is exactly the same as that illustrated in Fig. 1 of the drawings and described above. Accordingly corresponding reference numerals have been used to identify corresponding parts of the two structures. In the modified construction, the two lower brackets 19' and 21' are provided with trunnion seats 19a' and 21a' of only slightly greater diameter than 30 the trunnions 26c and 26d which permit rotation but not sliding movement of the trunnions. Fuse tube dropout movement is obtained by permitting collapse of a hinge joint between the supporting arm 26 and the fuse tube incident to fuse 40 rupture. Specifically, the arm 26 is provided with an enlarged end 40 hinged to the projecting nose 41a of the lower fuse tube ferrule 41 by means of a pivot pin 42. The enlarged arm end 40 is slotted as indicated at 43 to receive the ferrule nose 41a. In order normally to lock the arm 26 and ferrule 41 against relative pivotal movement, the extracting arm 33 is provided with a locking nose 44 which is adapted to seat within aligned nose receiving notches 41b, 40c and 40d in the nose and arm parts 41a, 40a and 40b, respectively, when the tube 25 and arm 26 occupy correct relative positions for mounting upon the support 10.

45 With this construction, the locking nose 44 contacts with the pivot pin 42 to lock the fuse tube 25 and the supporting arm 26 against relative pivotal movement so long as the extracting arm 33 is held against the supporting arm 26 by the fuse pigtail conductor 31. When, however, the fuse to which the conductor 31 extends is ruptured to permit downward movement of the extracting arm 33 under the influence of the spring 20, the locking nose 44 is instantly withdrawn 50 from the notches 40c, 41b and 40d, thus freeing the tube 25 and arm 26 for relative pivotal movement. This permits the tube 25 to move downward under the influence of gravity and the upper end spring thrust to disengage the tube 55 end part 29 from the retaining element 14 and

11

thus free the tube for dropout movement. Such downward movement of the fuse tube is accompanied by double pivotal movement of the supporting arm 28 about the axis of the trunnions relative to the support 10 and the pin 42 relative to the fuse tube 25.

While there have been described what are at present considered to be the preferred embodiments of the invention, it will be understood that various modifications may be made therein which are within the true spirit and scope of the invention as defined in the appended claims.

I claim:

1. A cutout of the dropout type comprising a support, a retaining element carried by said support, a fuse tube assembly including a fuse tube provided at one end with a part engageable with said element to restrain said assembly against dropout movement, a supporting member rigidly connected to said fuse tube and provided with pivot means, non-movable supporting means fixedly carried by said support for supporting said pivot means for pivotal movement and for translatory movement away from said retaining element, said fuse tube, supporting member and pivot means being movable as a unit with respect to said supporting means to release said part from said element and thus permit pivotal dropout movement of said assembly as said pivot means is translated away from said element, and fuse controlled means for normally preventing movement of said pivot means away from said element.

2. A cutout of the dropout type comprising a support, a retaining element carried by said support, a fuse tube provided at one end with a part engageable with said element to restrain said assembly against dropout movement and at its opposite end with supporting means rigidly mounted thereon, non-movable means fixedly carried by said support to slidably support said supporting means for sliding movement away from said retaining element in a direction substantially transverse to the axis of said tube, thereby to increase the distance between said supporting means and said element and thus permit dropout movement of said assembly without relative movement between said tube and said supporting means, and fuse controlled means for normally preventing said guided movement of said opposite tube end.

3. A cutout of the dropout type comprising a support, a retaining element carried by said support, a fuse tube assembly including a fuse tube provided at one end with a part engageable with said element to restrain said assembly against dropout movement and a laterally extending supporting arm rigidly connected to said fuse tube and provided with pivot means, non-movable means fixedly carried by said support to coact with said pivot means in providing for movement of said assembly bodily relative to said support without relative movement between said fuse tube and said supporting arm, thereby to effect movement of said pivot means away from said element, said end part being released from said element to permit dropout movement of said assembly as said pivot means moves away from said element, and fuse controlled means for normally preventing said movement of said assembly.

4. A cutout of the dropout type comprising a support, a retaining element carried by said support, a fuse tube assembly including a fuse tube provided at one end with a part engageable with

12

said element to restrain said assembly against dropout movement, a supporting member rigidly connected to said fuse tube and provided with pivot means, non-movable supporting means fixedly carried by said support for supporting said pivot means for pivotal movement and for translatory movement away from said retaining element, said fuse tube, supporting member and pivot means being movable as a unit with respect to said supporting means to release said part from said element and thus permit pivotal dropout movement of said assembly as said pivot means is translated away from said element, and spring biased fuse extracting means operative normally to prevent movement of said pivot means away from said element.

5. A cutout of the dropout type comprising a support, a retaining element carried by said support, a fuse tube assembly including a fuse tube provided at one end with a part engageable with said element to restrain said assembly against dropout movement, a supporting member rigidly connected to said fuse tube and provided with pivot means, supporting means carried by said support for supporting said pivot means for both pivotal movement and translatory movement away from said retaining element, said assembly being movable with respect to said supporting means to release said part from said element and thus permit pivotal dropout movement of said assembly as said pivot means moves away from said element, a fuse extracting arm pivotally supported by said supporting member and adapted for fuse restraint against pivotal movement relative to said supporting member, and biasing means carried by said support to coact with said arm in preventing movement of said pivot means away from said element and biasing said arm toward fuse extracting movement.

6. A cutout of the dropout type comprising a support, a retaining element carried by said support, a fuse tube provided at one end with a part engageable with said element to restrain said tube against dropout movement, a supporting arm rigidly connected to said fuse tube at the opposite end thereof and extending laterally therefrom, pivot means at the extended end of said arm, means carried by said support for supporting said pivot means for both pivotal movement and translatory movement away from said element, said tube and arm being movable as a unit to release said part from said element and thus permit pivotal dropout movement of said tube as said pivot means moves away from said element, a fuse extracting arm pivotally mounted upon said supporting arm adjacent the extended end of said supporting arm, said extracting arm being adapted for fuse restraint against pivotal movement relative to said supporting arm, and biasing means carried by said support to coact with said extracting arm in preventing movement of said pivot means away from said element and biasing said extracting arm toward fuse extracting movement.

7. A cutout of the dropout type comprising a support, a retaining element carried by said support, a fuse tube provided at one end with a retaining part engageable with said element to restrain said tube against dropout movement and having an open opposite end from which an extractable fuse link conductor is adapted to project, a supporting arm extending transversely away from the open end of said tube and provided with transversely spaced end parts at its

extended end, bearing elements extending transversely of said arm outwardly from said end parts, an extracting arm adapted for connection with the projected end of a fuse link conductor and supported upon said supporting arm for pivotal movement about the axis of said bearing elements, said extracting arm including a camming portion disposed between said end parts, means carried by said support to coact with said bearing elements in providing for both pivotal movement of said tube and translatory movement of said bearing elements away from said retaining element, said tube and supporting arm being movable as a unit to release said retaining part from said retaining element and thus permit pivotal dropout movement of said tube as said bearing elements move away from said retaining element, and biasing means carried by said support and including a part coacting with said camming portion to prevent movement of said bearing elements away from said retaining element and to bias said extracting arm for fuse extracting movement.

8. A cutout of the dropout type comprising a support, a retaining element carried by said support, a fuse tube provided at one end with a retaining part engageable with said element to restrain said tube against dropout movement and having an open opposite end from which an extractable fuse link conductor is adapted to project, a supporting arm extending transversely away from the open end of said tube and provided with transversely spaced end parts at its extended end, bearing elements extending transversely of said arm outwardly from said end parts, an extracting arm adapted for connection with the projected end of a fuse link conductor and supported upon said supporting arm for pivotal movement about the axis of said bearing elements, said extracting arm including a camming portion disposed between said end parts, spaced hinge brackets carried by said support and provided with bearing seats for supporting said bearing elements for translatory movement in a direction substantially normal to the longitudinal axis of said tube, thereby to provide for movement of said bearing elements away from said retaining element, said tube and supporting arm being movable as a unit to release said retaining part from said retaining element and thus permit pivotal dropout movement of said tube as said bearing elements move away from said retaining element, and biasing means carried by said support and including a part extending between said brackets to react between said support and said camming portion thereby normally to prevent movement of said bearing elements away from said retaining elements and to bias said fuse extracting arm for fuse extracting movement.

9. A cutout of the dropout type comprising a support, a retaining element carried by said support, a fuse tube provided at one end with a part engageable with said element to restrain said tube against dropout movement, a supporting member rigidly connected to said fuse tube and provided with pivot means, non-movable bracket means fixedly carried by said support and provided with bearing seats for supporting said pivot means for translatory movement therealong in a direction substantially normal to the longitudinal axis of said tube, thereby to provide for movement of said pivot means away from said element, said tube and supporting member being movable as a unit to release said part from said element and thus permit pivotal dropout movement of

said tube as said pivot means is translated away from said element, and fuse controlled means for normally preventing movement of said pivot means along said seats.

10. A cutout of the dropout type comprising a support, a retaining element carried by said support, a fuse tube provided at one end with a part engageable with said element to restrain said tube against dropout movement, a supporting arm rigidly connected to said fuse tube at the opposite end thereof and extending laterally therefrom, pivot means at the extended end of said arm, bracket means carried by said support and provided with bearing seats for supporting said pivot means for translatory movement therealong in a direction substantially normal to the longitudinal axis of said tube, thereby to provide for movement of said pivot means away from said element, said tube and supporting arm being movable as a unit to release said part from said element and thus permit pivotal dropout movement of said tube as said pivot means moves away from said element, a fuse extracting arm pivotally mounted upon said supporting arm adjacent the extended end of said supporting arm, said extracting arm being adapted for fuse restraint against pivotal movement relative to said supporting arm, and biasing means carried by said support to coact with said extracting arm in preventing movement of said pivot means along said seats and biasing said extracting arm for fuse extracting movement.

11. In a fused cutout, a support provided with a pair of spaced brackets having aligned trunnion receiving openings therein, a fuse tube having an open end from which an extractable fuse link conductor is adapted to project, a supporting arm extending laterally away from the open end of said tube and provided at its extended end with transversely extending trunnions engageable with said brackets through said openings pivotally to support said fuse tube upon said brackets for rotation into closed circuit position, spring means carried by said support and including a part extending between said brackets, a flat strip extracting arm adapted for connection with the projected end of a fuse link conductor, and pivot means supporting said extracting arm upon said supporting arm for pivotal movement about the axis of said trunnions, said flat strip extracting arm being bent adjacent the pivoted end thereof to provide a camming surface engageable with said spring part to tension the fuse link conductor as said fuse tube is rotated about the axis of said trunnions into its closed circuit position.

12. In a fused cutout, a support provided with a pair of spaced brackets having aligned trunnion receiving seats therein, a fuse tube having an open end from which an extractable fuse link conductor is adapted to project, a supporting arm extending laterally away from the open end of said tube and provided at its extended end with transversely extending trunnions engageable with said seats pivotally to support said fuse tube upon said brackets for rotation into closed circuit position, spring means carried by said support and including a part extending between said brackets, a flat strip extracting arm provided at one end with a reversely bent portion overlying an intermediate portion of said arm, means cooperating with said two arm portions for securely connecting the projected end of a fuse link conductor to said arm, and pivot means supporting said extracting arm at the opposite

end thereof upon said supporting arm for pivotal movement about the axis of said trunnions, said flat strip extracting arm being bent adjacent the pivoted end thereof to provide a camming surface engageable with said spring part to tension the connected fuse link conductor as said fuse tube is rotated about the axis of said trunnions into its closed circuit position.

13. A cutout of the dropout type comprising a support, a retaining element carried by said support, a fuse tube provided at one end with an end part engageable with said element to restrain said assembly against dropout movement, a supporting arm, hinge means pivotally connecting said supporting arm to said tube adjacent the other end thereof, said arm extending laterally away from said other end of said tube and being provided with pivot means at its extended end, an extracting arm pivotally supported upon said supporting arm and provided with a fuse controlled swing end co-acting with said hinge means normally to hold said tube and supporting arm against relative pivotal movement, bracket means carried by said support and coacting with said pivot means to support said fuse tube for rotation into closed circuit position wherein said tube end part engages said retaining element, and biasing means carried by said support and including a part engageable by said extracting arm as said tube is rotated into its closed circuit position to bias said extracting arm for fuse extracting movement, said hinge means being released in response to fuse extracting movement of said extracting arm to permit relative pivotal movement between said tube and supporting arm and thus provide for dropout movement of said fuse tube.

14. A cutout of the dropout type comprising a support, a retaining element carried by said support, a fuse tube provided at one end with an end part engageable with said element to restrain said assembly against dropout movement, a supporting arm, hinge means pivotally connecting said supporting arm to said tube adjacent the other end thereof, said arm extending laterally away from said other end of said tube and being provided with pivot means at its extended end, an extracting arm pivotally supported upon said supporting arm and provided with a fuse controlled swing end coacting with said hinge means normally to hold said tube and supporting arm against relative pivotal movement, said extracting arm being provided with a camming portion adjacent its point of pivotal support upon said supporting arm, bracket means carried by said support and coacting with said pivot means to support said fuse tube for rotation into closed circuit position wherein said tube end part engages said retaining element, and biasing means carried by said support and including a part engageable by said camming portion of said extracting arm as said tube is rotated into its closed circuit position to bias said extracting arm for fuse extracting movement, said hinge means being released in response to fuse extracting movement of said extracting arm to permit relative movement between said tube and supporting arm and thus provide for dropout movement of said fuse tube.

15. A cutout of the dropout type comprising a support, a retaining element carried by said support, a fuse tube provided at one end with an end part engageable with said element to restrain said assembly against dropout movement, a supporting arm, hinge means pivotally connecting

said supporting arm to said tube adjacent the other end thereof, said arm extending laterally away from said other end of said tube and being provided with transversely extended end parts, 5 trunnions extending from said end parts transversely outward from said arm, an extracting arm provided with camming means disposed between said end parts and with a fuse controlled swing end coacting with said hinge means normally to hold said tube and supporting arm against relative pivotal movement, pivot means supporting said extracting arm upon said supporting arm for pivotal movement about the axis of said trunnions, spaced brackets carried by said support 10 and provided with seats for seating said trunnions, thereby to support said tube for rotation into closed circuit position wherein said tube end part engages said retaining element, and biasing means carried by said support and provided with a part extending between said brackets to engage said camming means as said tube is rotated into its closed circuit position, thereby to bias said extracting arm for fuse extracting movement, said hinge means being released in response to 15 fuse extracting movement of said extracting arm to permit relative movement between said tube and supporting arm and thus provide for dropout movement of said fuse tube.

16. For use in a fused cutout, a fuse pigtail extracting arm comprising a flat strip adapted for pivotal support and having a pigtail extracting end removed from the point of pivotal support, said strip being provided with a return bent portion at its extracting end which overlies an intermediate portion thereof, and means extending from said intermediate portion of said strip and cooperating with said return bent portion for anchoring a fuse pigtail and for holding said pigtail in clamping engagement with said return bent portion of said element.

17. For use in a fused cutout, a fuse pigtail extracting arm comprising a flat strip adapted for pivotal support and having a pigtail extracting end removed from the point of pivotal support, 45 said strip being provided with a return bent portion at its extracting end which overlies an intermediate portion thereof, said return bent portion having an opening therethrough, a tie post fixedly mounted upon said intermediate portion 50 of said strip and extending through said opening, and a head mounted upon the extended end of said post, whereby a fuse pigtail may be wrapped around said post between said head and the return bent portion of said arm to be clamped 55 between said head and the return bent portion of said arm.

18. A cutout of the dropout type comprising supporting means, a fuse tube assembly including fuse extracting means, means for mounting 60 said fuse tube assembly upon said supporting means for dropout movement, and biasing means carried by said supporting means and engageable with said fuse extracting means to restrain said assembly against dropout movement and to bias 65 said fuse extracting means for fuse extracting movement.

19. A cutout of the dropout type comprising supporting means, a fuse tube assembly including fuse extracting means, means for mounting 70 said fuse tube assembly upon said supporting means for dropout movement, and biasing means carried by said support and including a part engaged by said extracting means as said assembly is moved into its closed circuit position to restrain 75 said assembly against dropout movement and to

bias said fuse extracting means for fuse extracting movement.

20. For use in a fused cutout, a fuse pigtail extracting arm comprising an elongated element adapted for pivotal support and having a pigtail extracting end removed from the point of pivotal support, said element being provided with a return bent portion at its extracting end which overlies an intermediate portion thereof, a tie post fixedly mounted upon said intermediate portion of said element and extending transversely past a part of said return bent portion of said element, and a head mounted upon the extended end of said post, whereby a fuse pigtail may be wrapped around said post between said head and the return bent portion of said element to be clamped between said head and the return bent portion of said element.

21. For use in a fused cutout, a fuse pigtail extracting arm comprising an elongated element adapted for pivotal support and having a pigtail extracting end removed from the point of pivotal support, said element having a curved camming portion disposed between said point of pivotal support and being provided with a return bent portion at its extracting end which overlies an intermediate portion thereof, a tie post fixedly mounted upon said intermediate portion of said element and extending transversely past a part of said return bent portion of said element, and a head mounted upon the extended end of said post, whereby a fuse pigtail may be wrapped around said post between said head and the return bent portion of said element to be clamped between said head and the return bent portion of said element.

22. For use in a fused cutout, a fuse pigtail extracting arm comprising an elongated element adapted for pivotal support and having a pigtail extracting end removed from the point of pivotal support, said element being provided with a return bend portion at its extracting end which overlies an intermediate portion thereof, and means supported by said intermediate portion of said element to extend transversely of said return bent portion for anchoring a fuse pigtail and for holding the fuse pigtail in clamping engagement with said return bent portion of said element.

23. For use in a fused cutout, a fuse pigtail extracting arm comprising an elongated element adapted for pivotal support and having a pigtail extracting end removed from the point of pivotal support, said element having a curved camming portion disposed between said point of pivotal support and said extracting end and being provided with a return bent portion at its extracting end which overlies an intermediate portion thereof, and means supported by said intermediate portion of said element to extend transversely of said return bent portion for anchoring a fuse pigtail and for holding the fuse pigtail in clamping engagement with said return bent portion of said element.

24. In a fused cutout of the dropout type, a support, a retaining element carried by said support, a fuse tube provided at one end with a retaining part engageable with said element to restrain said tube against dropout movement, a supporting member mounted on said tube adjacent the opposite end thereof and provided with trunnions laterally displaced from said tube, spaced brackets fixedly carried by said support and provided with elongated bearing seats for supporting said trunnions for pivotal and translatory movement, curved camming means on said supporting member positioned to move toward said brackets as said fuse tube and supporting member are pivoted about the axis of said trunnions to move said retaining part into engagement with said retaining element, and spring biased cam engaging means carried by said support and including a part extending between said brackets to engage said camming means and prevent translatory movement of said trunnions along said bearing seats after said tube and supporting member have been pivoted to effect engagement of said retaining part with said retaining element.
25. In a fused cutout of the dropout type, an elongated support, a retaining element carried by said support adjacent one end thereof, a fuse tube provided at one end with a retaining part engageable with said element to restrain said tube against dropout movement, a supporting member mounted on said tube adjacent the opposite end thereof and provided with trunnions laterally displaced from said tube, spaced brackets fixedly mounted upon the other end of said support to extend away from said other end of said support and provided with elongated bearing seats for supporting said trunnions for pivotal and translatory movement, curved camming means on said supporting member positioned to move toward said brackets as said fuse tube and supporting member are pivoted about the axis of said trunnions to move said retaining part into engagement with said retaining element, and a U-shaped spring having one leg mounted upon said other end of said support and the other leg extending between said brackets to engage said camming means and prevent translatory movement of said trunnions along said bearing seats after said tube and supporting member have been pivoted to effect engagement of said retaining part with said retaining element.
